UNITED STATES PATENT OFFICE.

MICHAEL E. NORMANDIN, OF LOS ANGELES, CALIFORNIA.

ADJUSTABLE AUXILIARY SHANK FOR SHOES.

1,091,696.

Specification of Letters Patent. Patented Mar. 31, 1914.

Application filed March 31, 1913. Serial No. 757,728.

To all whom it may concern:

Be it known that I, MICHAEL E. NORMANDIN, a citizen of Canada, and residing in the city of Los Angeles, county of Los Angeles, and State of California, have invented a new and useful Improvement in Adjustable Auxiliary Shanks for Shoes, of which the following is a specification.

This invention relates to shoe shanks, and the principal object is to provide a shoe shank having means to adjust the same, so that the instep may be altered to accommodate variations in the pedal arch without affecting the external appearance of the shoe.

It is a further object to provide a shoe shank that will positively support and maintain the desired shape of the shoe intermediate the heel and the ball thereof, together with adjusting means to properly fit the shoe to accommodate changes due to wear or loss of resiliency in the shank.

In the drawings accompanying this specification Figure 1 is an elevation of a shoe showing the sole and upper broken away, this invention being disclosed in side elevation in relation to the shoe. Fig. 2 is a plan view of the outer sole with the invention applied thereto. Fig. 3 is a detail section on the line 3-3 of Fig. 2. Fig. 4 is a detail section view of a modification showing an upset threaded bore formed of the metal composing the shank. Fig. 5 is a plan view of the same.

More specifically in the drawings, 5 designates a shoe having a sole 6 connected with the heel 7, the intermediate portion unsupported or not resting on the ground commonly called the instep, having applied intermediate the two portions of the sole forming the same the metallic shank 8, preferably struck up from a sheet of stiff light weight metal, or formed of other material. The sides 9 intermediate of the two ends of the plate are bent up at right angles to form a truss or brace to the plate, so that its arched form will not be readily broken down. This shank or reinforcement to the instep is preferably provided with a bore reinforced by a block 10 of sufficient thickness to carry enough threads therein and vertically disposed there-through to carry an adjusting screw 11, the head of which extends outside a portion of the sole forming the instep, and is adapted to be concealed by means of a flap 12 of leather formed by a scarf in the outer sole. An auxiliary member or shank

14 is also formed of metal, may be arched, and is preferably so bent longitudinally that it forms a smooth surface under the inner sole 15 with which it is permanently in contact. To fix this member 14 in relation to the shank 8, suitable fastenings 16 are carried through the two members, preferably at the heel portion, and shown as securing the two members to the heel. The toe end of this member is free, but the shank proper is secured to the sole portion by suitable fastenings.

In order to apply more resiliency to the auxiliary member and form a bearing surface for the screw to take up upon, the metallic strip 17 is secured to the under surface of the auxiliary member 14 by means of the rivets 18, this member being preferably formed similar to a leaf spring and having a hump 19 against the underside of which the screw 11 bears.

To provide a cheaper form of shank, and where the metal is not of sufficient thickness to form enough threads for the engagement of the screw, the metal adjacent the point where it is desired to place the adjusting screw is upset to form a plurality of tongues 20 and 21, whose adjacent portions are formed parallel with the inner surface of the plate, the metal being threaded, and the threaded portions of these tongues, form a greater bearing surface, and also when pressure is applied to the screw, tend to force these tongues in more positive engagement at the threaded portion of the screw, and securely lock or bind the latter in fixed adjustment.

The invention will be readily understood from the description and drawings, it being possible to alter the shape of the instep of shoes having this invention applied thereto, so that individual variations in a different pair of feet may be accommodated, or tendency to flat foot may be corrected, and the loss of resiliency due to use and possible crystallization in component members of the shank which would permit their flattening out or failure, may be taken up as desired by means of the adjustment.

What I claim is:

1. In combination with a shoe having an inner and outer sole, a metallic shank rigidly secured to the upper face of the outer sole adjacent the instep portion, said shank being disposed between the two soles, a resilient member mounted longitudinally on

said shank, one end of said member being rigidly secured thereto, and adjusting means operable from the exterior of said shoe adapted to raise or lower said resilient member to alter the configuration of the inner sole.

2. In combination with a shoe having an inner and outer sole, a metallic shank rigidly secured to the upper face of the outer sole 10 adjacent the instep portion, said shank being disposed between the two soles, a spring member mounted longitudinally on said shank, one end of said member being rigidly secured thereto, a second spring member 15 mounted on the under face of the first spring member, and adjusting means operable from the exterior of said shoe and adapted to raise or lower said spring members to alter the configuration of the inner sole.
- 20 3. In combination with a shoe having an inner and outer sole, a metallic shank rigidly

secured to the upper face of the outer sole adjacent the instep portion, said shank being disposed between the two soles, a spring member mounted longitudinally on said shank, one end of said member being rigidly secured thereto, a second spring member 25 secured to the under face of said first mentioned spring member, a screw bearing formed on said metallic shank, and a screw 30 through the outer sole of said shoe and passing through said screw bearing in said shank to raise or lower the resilient member to alter the configuration of the inner sole.

In witness that I claim the foregoing I have hereunto subscribed my name this 17th day of March, 1913.

M. E. NORMANDIN.
